US00D865394S

(12) **United States Design Patent** (10) Patent No.: **US D865,394 S**
(45) Date of Patent: **** Nov. 5, 2019**

(54) **PAPER PRODUCT DISPENSER WITH DYNAMIC ADVERTISING DISPLAY**

(71) Applicants: **Nathan Elliot**, Regina (CA); **Dwayne Melcher**, Regina (CA); **Paul Drouin**, White City (CA); **Trevor Thomas**, Regina (CA)

(72) Inventors: **Nathan Elliot**, Regina (CA); **Dwayne Melcher**, Regina (CA); **Paul Drouin**, White City (CA); **Trevor Thomas**, Regina (CA)

(**) Term: **15 Years**

(21) Appl. No.: **29/575,235**

(22) Filed: **Aug. 23, 2016**

(51) LOC (12) Cl. **20-02**

(52) U.S. Cl.

USPC **D6/518**

CLAIM

The ornamental design for a paper product dispenser with dynamic advertising display, as shown and described.

DESCRIPTION

The sole FIGURE is a front perspective view of a paper product dispenser with dynamic advertising display showing our design.

The broken lines shown in the sole FIGURE represent portions of the paper product dispenser with dynamic advertising display that form no part of the claimed design.

1 Claim, 1 Drawing Sheet
